His Attorney

UNITED STATES PATENT OFFICE.

CARL KERN, OF BERLIN-TEMPELHOF, GERMANY, ASSIGNOR TO GENERAL ELECTRIC COMPANY, A CORPORATION OF NEW YORK.

ELECTRIC SIGN.

Application filed November 28, 1923. Serial No. 677,555.

To all whom it may concern:

Be it known that I, CARL KERN, a citizen of the German Realm, residing at Berlin-Tempelhof, Germany, have invented certain 5 new and useful Improvements in Electric Signs, of which the following is a specification.

My invention relates to electric signs and in particular to signs of the character in 10 which discharge tubes are used in the form of letters.

The transportation of the mountings and other parts of an electric sign using discharge tubes involves great difficulties 15 from the fact that the tubes are easily broken.

Among the objects of my invention are to provide tubes that are satisfactorily transported and easily taken apart and exchanged; to provide for each tube a supporting plate on the front portion of which are located the tube which forms the letters or signs and on the rear of each plate the electrodes, in order that such electrodes may 20 not interfere with the light radiation. The supporting plate according to the improvement also serves as a support for other devices such as voltage regulators and the like. A row of these supporting plates may be arranged, the plates being located side by side. Since each supporting plate represents a 25 letter or character, an illuminated sign may be thus easily and conveniently assembled.

All the details of the means provided and 30 tending to increase the efficiency and serviceability of an electric sign of the above character are hereinafter more fully set forth and claimed. Referring to the accompanying drawing, one form of construction of 35 supporting plate and discharge tube representing one of the letters of the alphabet is shown in Fig. 1, in front elevation. In Fig. 2, the same device is shown in bottom plan. Fig. 3 is a diagrammatic illustration of the 40 connections of a plurality of discharge tubes with condensers, the tubes and condensers being connected in multiple. The discharge tube, as shown in the drawing, is bent in the form of the letter N. The tube, of course, 45 can be bent in the form of any letter or character. The forward sign-forming glass parts a of the tube are located in front of the metal plate b. Behind the metal plate are located electrodes c. The portion of the

discharge tube which contains the electrode 55 projects rearwardly from the section a and passes through an opening in the plate b. By this arrangement, the electrodes are prevented from interfering with or detracting from the sign. As indicated in the drawing, the tube in front of the plate is secured to the plate by suitable straps. Similarly, the portion of the tube which contains the electrodes is secured to the back of the plate by suitable stays or straps. In the drawing 60 and secured to the back of plate b, I show a voltage regulating device d, which device may be a condenser made up in the form of three tubes and which condenser, if used, effects the necessary equalization of the voltage in case the tubes are connected in parallel. With the construction shown, each discharge tube with its plate and regulating device, forms a complete unit. The plate protects the electrode in transportation and 65 in addition enables the formation of a unit which may be easily mounted or exchanged in the event of breakage. It will be understood that in the formation of the illuminated sign, a number of such units are assembled in proper order and that the electrodes of all the units may be connected in parallel with a suitable source of current; for example, the letter shown in Fig. 1 is N. If we assume that Fig. 2 represents a similar 70 duplicate unit with the letter O, then the combination of the two side by side would produce a sign displaying the word NO and the electrode c in Fig. 1 would be connected with the electrode c in Fig. 2, both of which 75 would be connected to a suitable source of current which may be represented by the wires shown in these figures. Similarly, the other electrodes c, Fig. 1, and c, Fig. 2, 80 would be connected to a suitable source of current. Where a voltage regulator is used, the regulator in each unit is connected in series with each letter, as indicated in the drawing.

It will be understood that the condensers 85 tend to restrict the consumption of current of the tubes thereby regulating the tension of the arc when the letters are connected in multiple as in Fig. 3. In this figure the tubes are connected in parallel across a 90 source of potential. As each of the tubes has a different length depending upon the shape of the letter, the tube having the 95

shortest length would, of course, be the first to become lighted if each of the tubes were not connected with condensers as indicated. Without the condensers the shortest tube 5 would prevent the other tubes from being lighted. This drawback is obviated through the accurate limitation of current consumption for each individual tube as affected by the inserted condensers. Obviously, different 10 kinds of condensers may be used, such as plate condensers or tube condensers. In the drawings I have indicated in Figs. 1 and 2 tube condensers, while in Fig. 3, I have indicated plate condensers.

15 While I have described my invention as embodied in concrete form in accordance with the provisions of the statutes, it should be understood that I do not limit my invention thereto, since various modifications 20 thereof will suggest themselves to those skilled in the art without departing from the

spirit of my invention, the scope of which is set forth in the annexed claims.

What I claim as new and desire to secure by Letters Patent of the United States, is,— 25

1. A unit for an electric sign comprising in combination a discharge tube, a supporting plate behind said tube, electrode terminals for said discharge tube projecting through said plate and secured to the rear 30 of the plate and electric condenser means mounted on the rear of said plate and connected in circuit with said tube.

2. An electric sign comprising a plurality of discharge tubes each in the form of a letter 35 each tube being connected in series with a condenser in a branch circuit and all of the branch circuits being connected in multiple.

In witness whereof, I have hereunto set my hand this 19th day of October, 1928.

CARL KERN.
